US00D770245S

(12) **United States Design Patent** (10) Patent No.: **US D770,245 S**
Repac (45) Date of Patent: ** Nov. 1, 2016

(54) **FOOD SLICER PART**

(71) Applicant: **Genius GmbH**, Limburg (DE)

(72) Inventor: **Cedomir Repac**, Brechen (DE)

(73) Assignee: **GENIUS GMBH**, Limburg (DE)

(**) Term: **14 Years**

(21) Appl. No.: **29/524,642**

(22) Filed: **Apr. 22, 2015**

Related U.S. Application Data

(63) Continuation of application No. 29/504,618, filed on Oct. 8, 2014.

(57) **CLAIM**

The ornamental design for a food slicer part, as shown.

DESCRIPTION

FIG. 1 is a top front left perspective view of a food slicer part showing my new design;

FIG. 2 is a right side elevational view thereof, the left side elevational view being the mirror image thereof;

FIG. 3 is a front elevational view thereof, the rear elevational view being the mirror image thereof;

FIG. 4 is a top plan top view thereof; and,

FIG. 5 is a bottom plan view thereof.

1 Claim, 4 Drawing Sheets
